COLLAPSIBLE SHELTER

Roger L. White, Lawrence, Kans., assignor to The Lawrence Paper Company, Lawrence, Kans., a corporation of Kansas

Application February 16, 1956, Serial No. 565,895

4 Claims. (Cl. 20—2)

This invention relates to shelters and more particularly to a novel shelter structure that is collapsible and foldable and easily erected to provide concealment to the occupant and also protection from the weather.

In shooting of wild fowl, such as ducks and the like, it is common practice to erect a blind, screen or pit for concealment of the hunter and to arrange decoys nearby whereby the hunter may shoot at the fowl attracted by the decoys. It is common practice to use branches, shrubbery, weeds, cornstalks and the like to provide a blind or screen but such structures are not movable to other desired locations as when the direction of the wind changes. Also, the weather is frequently inclement, for example, cold, wet and windy, and blinds formed of brush and the like do not fully protect the hunter from the weather.

The objects of the present invention are to provide a lightweight, portable, collapsible shelter that is easily and quickly erected; to provide such a structure with walls of moisture-resistant paperboard; to provide such a structure wherein the paperboard is adapted to be folded and the top member of the shelter formed in a container for the side walls and supports or posts of the shelter; to provide such a shelter that is easily manipulated for freedom of shooting; to provide such a structure with holders for camouflage material; and to provide a shelter structure adaptable for serving as a duck blind, camping shelter, child's playhouse and the like that is relatively inexpensive, economical to manufacture, yet sturdy, durable and easily erected and disassembled for repeated use.

In accomplishing these and other objects of the present invention, I have provided improved details of structure, the preferred forms of which are illustrated in the accompanying drawings, wherein:

Fig. 1 is a perspective view of the collapsible shelter in erected condition.

Fig. 2 is a horizontal sectional view through the shelter.

Fig. 3 is a partial vertical sectional view through the shelter on the line 3—3, Fig. 1.

Fig. 4 is a perspective view of the shelter in disassembled packaged condition.

Fig. 5 is a perspective view of the shelter showing the sides partially applied to the supports.

Fig. 6 is a perspective view of a modified form of shelter with camouflage holding devices thereon and with the top partially lifted.

Referring more in detail to the drawings:

1 designates a collapsible shelter which generally includes a plurality of spaced supports or posts 2, a side wall forming strip 3 and a top or cover member 4. The supports 2 are preferably posts or rods formed of metal, wood or other suitable material with one end 5 of each pointed whereby said pointed end may be forced into the ground sufficiently to firmly hold the post in upright position.

The side forming strip is preferably formed of a sheet of paper material having a width corresponding to substantially the desired height of the shelter and a length

2

corresponding substantially to the perimeter of the shelter. The strip 3 is preferably of paperboard such as solid paperboard or double-faced corrugated board suitably scored for folding or single-faced corrugated board of sufficient inherent rigidity transversely of the strip to stand on edge without slumping. The strip 3 forms the side walls 6 of the shelter and the outer face 7 of the side walls suitably waxed or otherwise treated to provide waterproofing or moisture resistance. It is also preferable that the paper sheet be of a type that all remain substantially stiff when wet. It is preferred that the posts 2 be of a length substantially corresponding to the width of the sheet 3. The ends of the strip 3 are folded inwardly from the face 7 as at 8 and turned to overlie the inner face 9 of the strip 10 with the marginal portion of the end secured as by staples 10 or by other suitable fastening devices to the body of the strip to form loops 11 of suitable size to be sleeved over the posts 2.

The top or cover member 4 is preferably formed of suitable double-faced corrugated paperboard of the type that will be substantially stiff while wet and preferably with an outer face 12 coated with wax or otherwise treated to make same substantially waterproof. The cover 4 is preferably formed from a substantially square or rectangular blank and provided with parallel score lines 13 and 14 spaced from adjacent edges 13' and 14' respectively a distance corresponding to the width of flanges 15 and 16 designed to overlie the upper portion of the shelter side walls 6. The blank is also provided with score lines 17 and 18 that are perpendicular to the score lines 13 and 14 and spaced from the edges 19 and 20 a distance substantially corresponding to the width of the flanges 15 and 16 to form flanges 21 and 22. Spaced parallel double score lines 23 and 24 extend across the blank in parallel relation to the score lines 13 and 14 with the spacing between the score lines 23 and 24 substantially corresponding to the width of the flanges 15 and 16. The flanges 21 and 22 are slotted from the edges thereof to the score lines 17 and 18 substantially in alignment with the score lines 13, 14, 23 and 24 to provide tabs 25 at the ends of the flanges 15 and 16. Each of the flanges 15, 16, 21 and 22 are turned inwardly with the tabs 25 underlying the flanges 21 and 22 and secured thereto as by staples or other suitable fastening devices 26 whereby the cover may be folded to form a carton 27 for containing the side strip 3 and posts 2. The spacing between the score line 23 and the score line 13 and the score line 24 and the score line 14 is such that when the carton is folded the flange 15 will overlie and substantially engage the flange 16. The length of the cover along the score line 14 between the score lines 17 and 18 is slightly greater than the width of the strip 3 and length of the posts 2 whereby they may be placed in the container formed by the cover 4. Also, the body 28 of the cover defined by the score lines 13, 14, 17 and 18, preferably substantially corresponds to the desired shape of a horizontal cross section through the completed shelter. All of the material for the shelter is contained in the carton formed by the cover member 4 and may be transported therein as desired.

When erecting the shelter, the carton 27 is opened and the posts 2 and strip 3 removed therefrom. Then the carton is further opened to the shape of the cover 4 and laid on the ground to rest on the edges of the flanges 15, 16, 21 and 22, and marks made on the ground to indicate the approximate corners of the shelter. The strip 3 is then opened and stood on edge approximately in the perimeter of the edges marked and the loops 11 at the ends thereof arranged in spaced relation approximately where the shelter door opening 29 is desired. Posts 2 are then driven approximately in the location

of the loops 11 and also in the approximate location of the adjacent corners thereto. The strip 3 is then raised and the loops 11 sleeved over the doorway posts with the strip exteriorly of the adjacent corner posts. Then the strip 3 is drawn by placing other posts 2 approximately in the other corners and pulling until the side wall forming portions are substantially tight, and then the other posts 2 are driven into the ground to provide adequate support to the side walls. Then the cover 4 is placed on the upper edges of the side walls of the shelter with the flanges depending from the body of the cover arranged exteriorly of the upper portion of the side walls 6 formed by the strip 3. The double score lines 23 and 24 are such that the portion therebetween and one of the side portions of the cover may be hinged upwardly if desired as when a hunter stands to shoot at fowl or other game, or the cover, being loose on the upper edges of the side walls, may be entirely lifted and thrown back for freedom of movement of the hunter. The structure of the shelter may be camouflaged as desired by placing branches, weeds and the like adjacent the sides and on the cover.

In the structure shown in Fig. 6, elastic tape 30 or other strands are arranged longitudinally of the strip 3 and suitably secured thereto at spaced intervals as at 31 to provide loops 32 that will aid in holding camouflaged material such as weeds and the like in position alongside of the shelter. Similar strands 33 of elastic or other suitable string, wire or the like are secured at spaced intervals to the cover 4 to also aid as ties or securing loops for holding camouflage material on the cover, particularly to hold such camouflage material on the cover in the event it is desirable to throw the cover back to provide freedom of movement during shooting of game.

If the strip 3 is formed of solid paperboard or double-faced corrugated paperboard, it is desirable that score lines 34 be arranged transversely of the strip approximately at the corners of the structure and also intermediate score lines 35 extending transversely of the strip substantially intermediate the score lines 34 whereby the side wall forming strip 3 may be folded to be placed in the carton formed by the cover 4. In using single-faced corrugated board, such score lines are unnecessary as the board may be folded as desired without injury thereto.

It is believed obvious I have provided a portable shelter that is economical to manufacture, easily packaged and transported and quickly erected at any desired site to provide a shelter suitable for children's playhouses as well as shelters for sportsmen.

It is to be understood that while I have illustrated and described certain forms of my invention, it is not to be limited to the specific forms or arrangement of parts herein described and shown except insofar as such limitations are included in the claims.

What I claim and desire to secure by Letters Patent is:

1. A collapsible shelter comprising, a plurality of rigid post members each having a sharpened end for insertion into the ground in spaced upright position with certain posts at the corners and others at the doorway of the shelter, a side wall sheet of paperboard that is inherently stiff in a direction transversely thereof and bendable on transverse lines to define the side walls of the shelter when said sheet is arranged on edge and wrapped exteriorly of the spaced posts, means securing the ends of the side wall sheet to the posts at the doorway of the shelter, a cover member of relatively stiff water-resistant paperboard having a central portion substantially corresponding in size and shape to the area defined by the side wall sheet with the margins of said central portion resting on the upper edges of said sheet, and flanges on the cover member and depending from said central portion and overlying the outer surface of the upper portion of the side walls, said posts having a length and said sheet having a width less than the length of one side of the shelter, said cover having spaced score lines extending across the

central portion in parallel relation to said one side whereby the cover is foldable to form a container for the side wall sheet and posts for transportation thereof.

2. A collapsible shelter comprising, a plurality of rigid post members each having a sharpened end for insertion into the ground in upright position, a side wall sheet of paperboard that is inherently stiff in a direction transversely thereof and having transverse lines extending thereacross for selective bending of the sheet of paperboard, said sheet of paperboard having reversely turned end portions with the end margins secured to the sheet to form loops for sleeving over certain spaced posts whereby the spacing therebetween defines a door opening of the shelter with the sheet arranged on edge with one edge resting on the ground and said sheet extending around the other posts set at spaced positions to define the corners of the shelter with the sheet defining the side walls of the shelter, a cover member of relatively stiff water-resistant paperboard having a central portion substantially corresponding in size and shape to the area defined by the side wall sheet with the margins of said central portion resting on the upper edges of said sheet, and flanges on the cover member and depending from said central portion and overlying the outer surface of the side walls, said posts having a length and said sheet having a width less than the length of one side of the shelter, said cover having spaced double score lines extending across the central portion in parallel relation to said one side whereby the cover is foldable to form a container for the side sheet and posts for transportation thereof.

3. A collapsible shelter comprising, a plurality of rigid post members each having a sharpened end for insertion into the ground, said posts having a spacing whereby certain posts form corner posts of the shelter and other posts are spaced to substantially define a door opening thereto, a side wall formed of a sheet of paperboard that is inherently stiff in a direction transversely thereof, means removably securing the ends of the paperboard to the door forming posts whereby the sheet of paperboard extends therefrom in engagement with the corner posts to define a substantially continuous side wall of the shelter, a cover member formed of relatively stiff paperboard supported on the upper edges of the side wall sheet, depending flanges on the cover member overlying the outer surface of the side wall sheet, said posts having a length and said side wall sheet having a height slightly less than the length of one side of the shelter, said cover having spaced double score lines extending thereacross in substantially parallel relation to said one side whereby the cover is foldable to form a container for the side sheet and posts for transportation thereof.

4. A collapsible shelter comprising, a plurality of rigid post members each having a sharpened end for insertion into the ground, said posts having a spacing whereby certain posts form corner posts of the shelter and other posts are spaced to substantially define a door opening thereto, a side wall formed of a sheet of paperboard that is inherently stiff in a direction transversely thereof, transverse lines extending across the paperboard for bending to define the corners of the shelter side wall, means removably securing the ends of the paperboard to the door forming posts whereby the sheet of paper board extends therefrom in engagement with the corner posts to define a substantially continuous side wall of the shelter, a cover member formed of relatively stiff paperboard supported on the upper edges of the side wall sheet, depending flanges on the cover member overlying the outer surface of the side wall sheet, said posts having a length and said side wall sheet having a height slightly less than the length of one side of the shelter, said cover having spaced double score lines extending thereacross in substantially parallel relation to said one side whereby the cover is foldable to form a container for the side sheet and posts for transportation thereof, strand means

extending longitudinally of the exterior of the side wall sheet and connected thereto at spaced intervals forming loops therebetween for securing camouflage materials thereto, and elongate strand means on the exterior of the cover with spaced portions secured thereto forming loops therebetween for securing camouflage material on said cover.
